UNITED STATES PATENT OFFICE.

SYDNEY D. TUCKER, OF TROY, NEW YORK.

CLASP.

SPECIFICATION forming part of Letters Patent No. 295,310, dated March 18, 1884.

Application filed December 21, 1883. (No model.)

To all whom it may concern:

Be it known that I, SYDNEY D. TUCKER, a resident of the city of Troy, in the county of Rensselaer and State of New York, have invented certain new and useful Improvements in Clasps; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

Similar letters refer to similar parts in the several figures therein.

My invention relates to improvements in clasps adapted for use in supporting stockings and other articles of wearing-apparel; and it consists in providing a web-supporting plate with a stud and bifurcated spring, and suitable means for opening and closing the spring-arms.

The objects of my invention are, first, to provide a clasp-plate to which the web may be easily and quickly attached; second, to provide suitable means for securing a stocking or other garment to a studded plate without injury to the fabric; third, to facilitate the operation of supporting clasps; fourth, to simplify and cheapen the construction of such clasps.

In the drawings I have represented by Figure 1 a plan view of a closed clasp; Fig. 2, a plan view of an open clasp; Fig. 3, a side view of an open clasp; Fig. 4, a plan view of a clasp-plate having the upper part cut off at broken line *x* in Fig. 3, and showing web *G* partially inserted in the plate; Fig. 5, a vertical section taken at broken line *x* in Fig. 4; Fig. 6, a central longitudinal section of slide *D*, taken at broken line *x* in Fig. 2; Fig. 7, a plan view of the reverse side of the plate fully secured to the web; Fig. 8, a perspective view of clasp attached to garment.

The plate *A* is provided with a headed stud, *C*, which is inserted within an aperture made in the plate. That portion of the plate *A* surrounding the aperture is swaged up into a plane higher than the general surface of the plate, as shown in Figs. 3 and 5, which gives additional strength to that portion of the plate and permits of the use of a shorter post for the

stud *C*. If a longer stud-post were used in a plate with a plane surface, more leverage would be afforded to crowd or pull the post out of a vertical position relative to the plate when in use. The plate is also provided with the hook-points *e e* and *g* at one end, and in the middle portion with the inwardly-projecting arms *j k*, which serve to hold the plate upon one end of the web *G*. The web is easily inserted by partially folding one end, so that the fold extends longitudinally of the web along its middle portion, and inserting the side edges of the web between the hooks *e e*, and flattening out the web again until the web occupies the position shown in Fig. 4. The hooks *e e* engage the web on the lower side, and the hook *g* on the upper side. The plate or clasp is then turned over, the web folded around the hooks *e e*, so that the fold extends transversely of the web, and inserted beneath the arms *j k*, as shown in Fig. 7, where it is securely retained by said arms and the hooks. The web is easily inserted beneath the arms by longitudinally folding the same and inserting the edges between the ends of the arms in the same manner as between the hooks *e e*; or one edge or side of the web may be inserted first, and the web folded so as to insert the other side or edge. Such a form of construction permits the easy and rapid insertion of webs of different widths in the same clasp without danger of the clasp slipping upon the web. The plate is also provided with a bifurcated spring, *B*, which may be either integral with the plate or attached thereto. The spring has two arms, *a* and *b*, provided on their contiguous edges or sides, at or near their free ends, with the circular depressions *c c'*, Fig. 2, and one of them with the struck-up edge *d*. The latter forms a thumb-rest, by pressing upon which the arms of the spring may be bent down to or near the plate *A*, the recesses *c c'* permitting the ends of the arms to freely pass up and down past the head of the stud *C* when the arms are open, as shown in Fig. 2. Without the rest *d* the thumb of the operator would strike stud-head *C* before the ends of the arms were forced beneath it. The arms are also provided with a slide, *D*, which is shown constructed of a single piece of sheet metal. The ends of a flat

strip of sheet metal are bent together to form a clasp, which surrounds both arms of the spring, as shown, and is adapted to slide thereon and close the arms upon the stud and prevent 5 their spreading. A front projecting piece, *n*, is bent upon itself, as shown in section in Fig. 6, and rests between the spring-arms, to force and keep them apart, being of sufficient width to spread the arms farthest apart at their free 10 ends. It is evident, therefore, that by sliding the slide *D* back and forth upon the arms they can be made to open and close at their free ends. The slide may have a projection, *m*, from its upper surface, to serve as a handle to 15 operate the slide.

To attach the clasp to a stocking or other garment, it is only necessary to insert the garment in the space between the spring-arms and the head of the stud when the clasp is open, as 20 shown in Figs. 2 and 3, press down the free ends of the spring-arms below the head of the stud, and push the slide forward to the position shown in Fig. 1, which forces the arms toward each other until their free ends occupy 25 a position beneath the head of the stud. The spring then forces the ends of the arms and the projection *n* of the slide up firmly against the fabric, and securely retains the same between these parts and the head of the stud, as shown 30 in Fig. 8. The fabric is thus secured on every side, and is not unduly strained in any portion, as has been the case with stud-clasps heretofore constructed. The thumb-rest *d*, projecting out from arm *b*, overlaps arm *a* 35 when the arms are spread, as well as when they are closed, which prevents the fabric from crowding up between the open arms when they are forced down upon it and below the head of the stud, as shown in Fig. 8. The arms *a* and 40 *b* form clamps, which, when closed, crowd the fabric under the head of the stud on every side, as shown in Fig. 8.

It is of the greatest importance to bind the fabric on the sides of the stud nearest the 45 weight to be supported as well as the remote sides, as such an arrangement transfers a large portion of the resistance to the fabric

which rests upon the ends of the spring-arms, thereby relieving the fabric which rests upon the edges of the head of the stud of undue strain.

What I claim as new, and desire to secure by Letters Patent, is—

1. The combination, in a clasp, of a studded plate, and spring-arms provided with suitable 55 means for spreading and closing said arms, substantially as described, and for the purposes set forth.

2. A clasp-plate provided at or near one end with hook-points *e e*, and at or near its middle portion with the inwardly-projecting arms *j k*, in combination with a mechanism, substantially as described, for attaching said plate to 60 a garment.

3. A studded clasp-plate adapted to be secured to a piece of webbing, having that portion of the plate contiguous to the stud swaged up to occupy a plane higher than that of the general surface of the plate, in combination with a suitable clamping device, whereby a 70 garment is secured to said stud, substantially as described, and for the purposes set forth.

4. A studded clasp-plate, in combination with clamping-arms, and slide provided with a spreading device, *n*, substantially as described, and for the purposes set forth. 75

5. A studded clasp-plate, in combination with a clamping-spring provided with a thumb-rest, *d*, integral therewith, and suitable means for operating said spring, substantially as described, and for the purposes set forth. 80

6. A studded clasp-plate, in combination with two clamping-arms provided with recesses *c c'* and projection *d*, attached to one prong and overlapping the other, and suitable 85 means for opening and closing said arms, substantially as described, and for the purposes set forth.

In testimony whereof I have hereunto set my hand this 19th day of December, 1883.

SYDNEY D. TUCKER.
